UNITED STATES PATENT OFFICE.

FREDERICK W. KLINEMAN, OF CHICAGO, ILLINOIS, ASSIGNOR OF ONE-HALF TO
J. G. BOSWELL, OF CHICAGO, ILLINOIS.

SPURIOUS-COIN DETECTOR FOR SLOT-MACHINES.

No. 911,247.

Specification of Letters Patent.

Patented Feb. 2, 1909.

Application filed October 12, 1908. Serial No. 457,212.

To all whom it may concern:

Be it known that I, FREDERICK W. KLINEMAN, a citizen of the United States, residing at Chicago, in the county of Cook and State of Illinois, have invented new and useful Improvements in Spurious-Coin Detectors for Slot-Machines, of which the following is a specification, reference being had to the drawings, forming a part thereof.

10 The purpose of this invention is to provide, for coin-operated or so-called "slot" machines, a spurious-coin detecting device constituted of the coin chute or pathway and guards of the coin in its entrance and advance toward the coin receptacle or position at which it may become an element in the means for operation of the machine.

15 It consists of the features of construction shown and described as indicated in the 20 claims.

In the drawings:—Figure 1 is a side elevation of a device embodying this invention, same being shown mounted on a case for a mechanism which is to be coin-operated. 25 Fig. 2 is a view of the device with the front plate partly broken away showing the interior. Fig. 3 is a section at the line 3—3 on Fig. 2. Fig. 4 is a view similar to Fig. 2, showing a modification.

30 The device shown containing the coin chute or path comprises a front plate, A, and a back plate, B, spaced apart by fillers, C, C¹, C² and C³, which are shaped and disposed so that the edges of some of them form the edges of 35 the coin chute or pathway between the plates, A and B. This coin chute or pathway comprises a portion, 2, leading from the entrance mouth, 1, at which the coin is deposited in a downwardly sloping advancing 40 direction, a descending portion, 3, leading to a horizontal portion, 4, and also a horizontal portion, 5, above the portion, 4, and leading off from the descending portion, 3. The terminal horizontal portion, 4, leads to 45 the case, D, for the mechanism which may be operated by the coin. This mechanism does not pertain to the present invention and is not illustrated in detail. It may be any mechanism which may be operated or whose 50 operation may be controlled by the discharge of coin thereinto from the discharge end, 6, of the coin chute. The branch portion, 5, is for spurious coins which are discarded there- 55 to as hereinafter explained, and are dis- charged therefrom at the final discard

mouth, 7, of said branch. Between the two plates, A and B, there is mounted a pusher, F, having a stem, F¹, extending out to the right and protruding from between the plates, A and B, at the right-hand end. A spring, 60 G, is provided for operating upon this pusher, holding it yieldingly at the most retracted position,—that is, with the stem or handle, F¹, protruded to the maximum beyond the right-hand end of the plates and exposed for 65 pushing the pusher inward against the resistance of the spring at which position it is stopped by the filler, C⁴. The forward or advance edge of this pusher constitutes the back edge of the descending portion, 3, of 70 the coin chute. It has a rearward extension, F², extending from the upper corner, f¹, back parallel with the handle and path of sliding movement under the filler, C, with whose under edge the extension, F¹, coincides, and beyond which the pusher protrudes when it is 75 thrust forward for action upon the coin hereinafter described, the length of said extension being sufficient to cause the end to be still engaged under the said filler, C, when 80 the pusher is thrust forward to the limit of its path of movement.

H is a magnet mounted upon the rear side of the device against and preferably protruding through the rear plate, B, so that its inner 85 face is substantially flush with the inner or forward surface of said rear plate. This magnet is located at or opposite the descending portion, 3, of the coin path in such position that the upper portion of the pusher, F, 90 travels past it when it is thrust forward for operating on the coin. The pusher, F, is preferably provided with a projection forming an upwardly-facing coin-supporting shoulder, f, located preferably somewhat less 95 than the diameter of the coin below the upper corner, f¹, of the pusher. The filler, C², which is interposed between the true-coin branch, 4, and the discard or spurious-coin branch, 5, has its upper corner, c¹, at the end 100 toward the pusher preferably slightly lower than the shoulder, f, of the pusher, for reason hereinafter explained. The lower edge of the filler, C¹, which forms the closure or guard of the coin chute at the upper side has the portion, c¹, moderately inclined from horizontal for a distance partly overhanging the descending portion, 3, of the coin path. The upper end of the magnet, H, which forms the 105 back wall of the upper part of the descending 110

portion, 3, of the coin chute extends high enough to be lapped a little by a coin which has rolled around the corner, c^1 , far enough so that the diameter of the coin running from 5 said corner lies below a line from said corner extending across the coin path to the nearest point of the opposite edge of the filler, C^1 . If a washer or disk of iron or other magnetic metal has been deposited instead of a true 10 coin, the attraction of the magnet is designed to halt it when it has lapped the magnet at the position indicated,—that is, when the diameter extending from the bearing of the coin on the corner, f , lying a little below a 15 line from the same corner to the nearest point of said inclined opposite edge, c^1 . When halted in this position the pusher, being thrust forward through the descending portion, 3, of the coin path, will push the coin 20 across said descending portion, the movement being at such an angle to the inclined edge, c^1 , that the coin will not be jammed or pinched between the pusher and said edge, but will be wedged downward by the inclined 25 edge as it is pushed onward by the pusher; and it will thus be forced past the upper corner, c^2 , of the filler, C^2 , before it is pushed off the magnet.

The distance between the pusher and the 30 end of the filler, C^2 , when the pusher is fully retracted by the spring is only sufficient to allow the true coin to pass down into the lower part of the descending portion, 3, of the chute, which is the entrance to the true 35 coin branch, 4. Any substantial forward movement, therefore, of the pusher operating upon a spurious coin which has adhered to the magnet will prevent it from passing down into the entrance to the true-coin 40 branch; and a push which exceeds half the diameter of the coin, carrying the center of the coin past a direct line through the corner, c^2 , of the filler, C^2 , will cause the coin, even if it were then released from the magnet, to 45 fall so as to roll into the discard branch, 5, and be discharged at the discard mouth, 6, even if the pusher should be retracted after such a half stroke. The coin-supporting shoulder, f , is to form a partially-supporting 50 seat for the coin so that if upon its being pushed along the path the action of gravity should cause it to descend as well as to move forward in the direction in which it is pushed, its descending tendency would be checked 55 by the support afforded by the shoulder, so that it would in any event be certain to be pushed into the discard branch. In order that if the magnet should be very weak, or the adhesion of the spurious coin should be 60 broken intentionally by jarring the device the coin would still pass into the discard chute and be pushed out, it is preferable to locate the shoulder, f , as described, a trifle higher than the corner, c^2 , of the filler, C^2 , so 65 that the coin, even if jarred loose from the

magnet, falling on the shoulder and being deflected onward by it, and still descending slightly in such deflection, would lodge on the upper edge of the filler, C^2 , and roll into the discard chute. A true coin deposited in 70 the slot will roll down the portion, 1, and around the corner, f^1 , on which it will be kept by the opposite portion, 8, of the edge of the filler, C^1 , which is shaped in the arc of a circle about that corner as a center, until its 75 course becomes distinctly downward; and from thence passing out from under the portion, 8, of said edge in the direction of a tangent thereto, it will follow the true path of a projectile, indicated by dotted line, 9, passing 80 over the shoulder, f , without striking it, and entering the gap between the end of the filler, C^2 , and the edge of the pusher into the lower part of the descending portion, 3, of the chute, and be halted thus at the entrance 85 into the true coin branch, 4. The plate, A, is apertured and provided with a glass panel, A^1 , opposite the said true-coin branch, 4, so that all coins standing therein will be visible from a considerable distance 90 to any one whose duty it may be to watch the machine. The length of this glass panel is sufficient to expose at all times at least two coins,—that is, one coin which may have halted at the foot of the descending 95 portion, 3, of the chute and another between that position and the discharge mouth. The pusher F, extending down along the entire rear edge of the descending portion, 3, forming the back wall of said rear edge to the bottom thereof must be pushed in by the operator after he has deposited his coin in order to obtain any action of the mechanism 100 which is controlled or released by the coin.

The machine will be first loaded with a 105 single coin or slug deposited in the usual manner and moved by the pusher onward in the horizontal true-coin branch, 4, so that it stands exposed to view through the glass panel at the farther end of said branch. 110 The first coin deposited for obtaining the action of the machine, if a true coin will fall into the rear end of this branch, 4, lodging therein immediately behind the preliminary coin with which the device has been loaded 115 for starting, and the depositor of the coin, pushing the pusher inward, will cause the coin which he has deposited to push the coin in advance of it out so as to operate or release the mechanism, leaving the coin just 120 deposited exposed to view, and when the pusher is retracted, a vacant space behind it for a new coin. Since this action of the pusher must be performed in order to obtain any result, the depositor of a spurious magnetic disk or washer, will, by this movement 125 of the pusher cause his spurious coin to be ejected into the discard branch, 5. If the spurious coin is non-magnetic,—as, for example, a brass disk,—it will fall into the 130

true-coin branch, and the depositor can operate the pusher and obtain the action of the machine, but the spurious coin which he has deposited will remain visible at the 5 farther end of the true-coin branch, 4, during his entire use of the mechanism which he has thus operated or released, so that a watcher will be able from a distance to detect the fraud and cause the arrest of the 10 culprit.

The device is especially designed for attachment of means to be operated by deposit of a nickel coin, and substantially the only metal which so nearly resembles nickel in 15 color as to defeat detection by reason of the difference in color is steel or polished iron, whose magnetic character will cause it to be discarded as described. Brass or copper will be discovered by their false color, and the 20 device will thus afford means for detecting substantially all spurious devices likely to be used, zinc or tin only of the non-magnetic materials cheaper than the true nickel coins being difficult to detect by this means.

25 In the modification shown in Fig. 4 there is added to the features and devices above described a trap gate, K, pivoted at its upper end so as to depend into the path of a spurious magnetic coin,—that is, the path which 30 such coin should take under the action of the pusher, F, in order to be delivered through the discard mouth. The purpose of this trap gate is to prevent the possibility of forcing the spurious coin back from the discard 35 branch into the descending portion of the coin path to cause it to reach the true coin branch, 4, as might possibly be done in the absence of such trap gate by means of a flat blade introduced through the discard mouth, 40 7, after the spurious coin has been driven by the pusher off the magnet into the discard branch, 5. With the trap gate hung, as shown, in position to be swung onward toward the discard mouth by the spurious coin 45 when pushed by the pusher, the spurious coin will be crowded downward somewhat by the resistance of the weight of the gate, which must be lifted by an elbow lodged on the shoulder, f, of the pusher before it has 50 been pushed off from or out of range of the influence of the magnet. Such lodgment, however, will support the slug so that it will unfailingly continue to push the trap gate before it until the center of the slug is carried past the vertical line of the corner, c², so 55 that it cannot fail to fall beyond that corner into the discard branch, 5, when relieved from the influence of the magnet. The trap gate is of such length that the coin descending over the elevated corner, c², to the lower 60 side of the discard branch passes out from under the end of the gate, which thereupon, by gravity, returns to its normal pendent position behind the coin. The trap gate is 65 stopped against swinging back toward the

pusher from this point by the shoulder, 9, of the filler, C¹, and the interval between the lower end of the gate at its pendent position and the elevated corner, c², of the filler, C², is less than the diameter of the coin so that the 70 coin cannot be pushed back after it has once passed the gate.

I claim:

1. A spurious-coin detector for slot machines comprising a coin chute in which the 75 coin advances on edge, and comprising a descending part; a coin pusher whose edge forms part of the edge wall of the chute at such descending part of the latter; a magnet disposed at the side of the coin path at such 80 descending part of the chute, said chute comprising a discard branch leading off from said descending part opposite the portion of the edge thereof formed by the pusher, and a true-coin branch leading off from such 85 descending part below the discard branch.

2. A spurious coin-detector for slot machines comprising a coin chute in which the coin advances on edge, and comprising a descending part; a pusher whose edge forms 90 part of the edge wall of the chute at such descending part of the latter; a magnet disposed at the side of the coin path at such descending part of the chute, said chute comprising a discard branch leading off from 95 the descending part opposite the portion of the edge thereof formed by the pusher, and a true-coin branch leading off from such descending part below the discard branch, said 100 edge of the pusher having a coin-supporting shoulder situated slightly above the level of the bottom of the entrance to the discard branch.

3. A spurious-coin detector for slot machines comprising a coin chute in which the 105 coin advances on edge, and comprising a descending part; a coin pusher whose edge forms part of the edge wall of the chute at such descending part of the latter; a magnet disposed at the side of the coin path at such 110 descending part of the chute, said chute comprising a discard branch leading off from said descending part opposite the portion of the edge thereof formed by the pusher, and a true-coin branch leading off 115 from such descending part below the discard branch, the upper edge wall of the chute being sloped with moderate deflection downward from horizontal at a portion overhanging said descending part.

4. A spurious-coin detector for slot machines comprising a coin chute in which the coin advances on edge, and comprising a descending part; a coin pusher whose edge forms part of the edge wall of the chute at such 125 descending part of the latter; a magnet disposed at the side of the coin path at such descending part of the chute, said chute comprising a discard branch leading off from 130 said descending part opposite the portion of the edge thereof formed by the pusher.

portion of the edge thereof formed by the pusher, and a true-coin branch leading off from such descending part below the discard branch, the pusher having a horizontal extension whose upper edge is substantially parallel with the pushing movement, the upper edge of said extension running to the upper corner of the pusher and being overhung by the lower or back edge wall of the 10 portion of the chute antecedent to said descending portion.

5. A spurious-coin detector for slot machines comprising a coin chute in which the coin advances on edge, and comprising a 15 descending part; a coin pusher whose edge forms part of the edge wall of the chute at such descending part of the latter; a magnet disposed at the side of the coin path as such descending part of the chute, said chute 20 comprising a discard branch leading off from said descending part opposite the portion of the edge thereof formed by the pusher; a true-coin branch leading off from such descending part below the discard 25 branch, and means for guiding the pusher in a substantially horizontal direction for thrusting its said edge through the descending portion of the chute.

6. A spurious-coin detector for slot machines comprising a coin chute in which the coin advances on edge, and comprising a descending part; a coin pusher whose edge forms part of the edge wall of the chute at such descending part of the latter; a magnet 35 disposed at the side of the coin path at such descending part of the chute, said chute comprising a discard branch leading off from said descending part opposite the portion of the edge thereof formed by the pusher; 40 a true-coin branch leading off from such descending part below the discard branch, means for guiding the pusher in a substantially horizontal direction for thrusting its said edge through the descending portion of 45 the chute, and a spring for retracting it.

7. A spurious-coin detector for slot machines comprising a coin chute in which the coin advances on edge, and comprising a descending part; a coin pusher whose edge 50 forms part of the edge wall of the chute at such descending part of the latter; a magnet disposed at the side of the coin path at such descending part of the chute, said chute comprising a discard branch leading off from 55 said descending part opposite the portion of the edge thereof formed by the pusher, and a true-coin branch leading off from such descending part below the discard branch, the pusher being extended to form the back 60 edge wall of the chute opposite the true-coin branch.

8. A spurious-coin detector for slot machines comprising a coin chute in which the coin advances on edge, and comprising a 65 descending part; a coin pusher whose edge

forms part of the edge wall of the chute at such descending part of the latter; a magnet disposed at the side of the coin path at such descending part of the chute, said chute comprising a discard branch leading off from 70 said descending part opposite the portion of the edge thereof formed by the pusher, and a true-coin branch leading off from such descending part below the discard branch, the true coin branch having an exposed 75 transparent side wall sufficient in extent for exposure to view therethrough of at least two coins.

9. A spurious-coin detector for slot machines comprising a coin chute in which the coin advances on edge, and comprising a 80 descending part; a coin pusher whose edge forms part of the edge wall of the chute at such descending part of the latter; a magnet disposed at the side of the coin path at such 85 descending part of the chute, said chute comprising a discard branch leading off from said descending part opposite the portion of the edge thereof formed by the pusher, and a true-coin branch leading off from such de- 90 scending part below the discard branch, the true-coin branch having an exposed transparent side wall sufficient in extent for exposure to view therethrough of at least 95 two coins, the pusher being extended to form the back wall of the chute opposite the true-coin branch, and the stroke of the pusher being substantially equal to one coin diameter.

10. A spurious-coin detector for slot machines comprising a coin chute in which the coin advances on edge, and comprising a descending part; a coin pusher whose edge forms part of the edge wall of the chute at such descending part of the latter; a magnet 100 disposed at the side of the coin path at such descending part of the chute, said chute comprising a discard branch leading off from said descending part opposite the portion of the edge thereof formed by the pusher; a trap 105 gate in said discard branch, and a true-coin branch leading off from the descending part below the discard branch.

11. A spurious-coin detector for slot machines comprising a coin chute in which the coin advances on edge and comprising a 115 descending part; a coin pusher whose edge forms part of the edge wall of the chute at such descending part of the latter; a magnet disposed at the side of the coin path at such 120 descending part of the chute, said chute comprising a discard branch leading off from said descending part opposite the portion of the edge thereof formed by the pusher; a true-coin branch leading off from such descending 125 part below the discard branch, said edge of the pusher having a coin-supporting shoulder situated slightly above the level of the bottom of the entrance to the discard branch, and a trap gate at the entrance to the discar

branch adapted to be swung onward in the discard branch by a spurious coin lodged on said shoulder.

12. A spurious-coin detector for slot machines comprising a coin chute in which the coin advances on edge and comprising a descending part; a coin pusher whose edge forms part of the edge wall of the chute at such descending part of the latter; a magnet disposed at the side of the coin path at such descending part of the chute, said chute comprising a discard branch leading off from said descending part opposite the portion of the edge thereof formed by the pusher; a true-

coin branch leading off from said descending part below the discard mouth; a trap gate suspended at the entrance to the discard branch free to swing onward in the latter, and stopped against swinging back into said descending part. 15

20 In testimony whereof, I have hereunto set my hand, in the presence of two witnesses, at Chicago, Illinois, this 6th day of October, 1908.

FREDERICK W. KLINEMAN.
